CLAIM

The ornamental design for a solar powered electronic display assembly with pole mount, as shown and described.

DESCRIPTION

FIG. 1 is a front perspective view of the solar powered electronic display assembly with pole mount;
FIG. 2 is a front elevation view thereof;
FIG. 3 is a rear elevation view thereof;
FIG. 4 is a right side elevation view thereof;
FIG. 5 is a left side elevation view thereof;
FIG. 6 is a top view thereof;
FIG. 7 is a bottom view thereof; and,
FIG. 8 is an environmental view thereof.

The broken lines shown represent environmental subject matter and form no part of the claimed design. The dot-dashed broken line(s) define the bounds of the claimed design and form no part thereof.
